ATTORNEYS

the pen or pencil is inserted into the pocket, the cam 9 is held in its normal position by the resilient arm 7 of the clip C. If the pen or pencil is withdrawn from the pocket, the cam 9 is caused to roll toward its high point, thereby increasing the tension of the spring clip 5, and the pen or pencil is held firmly in the pocket. The cam 9 is held in its normal position by the resilient arm 7 of the clip C. If the pen or pencil is withdrawn from the pocket, the cam 9 is caused to roll toward its high point, thereby increasing the tension of the spring clip 5, and the pen or pencil is held firmly in the pocket.

UNITED STATES PATENT OFFICE

2,612,669

ANTILOSS DEVICE

Gilbert M. Brueckner, Milwaukee, Wis.

Application August 23, 1948; Serial No. 45,605

1 Claim. (Cl. 24-11)

1

This invention appertains to pen and pencils and more particularly to an anti-loss attachment therefore.

Fountain pens and mechanical pencils are universally provided with some type of spring clip for engagement with the pocket of the owner to hold the same in place. In actual practice, the pens and pencils have a tendency to gradually ride out of the pocket and if the wearer bends over, there is a likelihood of the pen or pencil falling out of the pocket; resulting in the loss or damage thereof. This is particularly disastrous with the costly pen and pencil sets now found on the market at the present time.

It is, therefore, one of the salient objects of my invention to provide an inconspicuous attachment for the clips or writing implements, which will automatically increase the tension of the spring clip on the pocket, if there is any tendency of the implement riding out of the pocket, thereby preventing the accidental loss of such implement.

Another primary object of my invention is to provide such an attachment which can be readily and naturally held in an inoperative position by the user during the intentional withdrawal of the implement from the pocket.

A further object of my invention is to provide an anti-loss attachment for the clips of writing implements embodying a cam pivotally carried by the lower free end of the clip for engagement with the pocket, adapted to automatically roll toward its high point upon the working out of the implement from the pocket for increasing the tension and the holding qualities of the clip upon the pocket, the cam arrangement being such that the greater the upward pull on the pens, the tighter the gripping of the cam upon the pocket.

A still further object of my invention is to provide a tooth on the extreme high point of the cam for insertion in the fabric of the pocket, so as to positively preclude the slipping of writing implements from the pocket should the cam ride to the extreme high point on the pocket.

With these and other objects in view the invention consists in the novel construction, arrangement and formation of parts, as will be hereinafter more specifically described, claimed, and illustrated in the accompanying drawing, in which drawing

Figure 1 is a fragmentary side elevational view of a fountain pen showing my novel attachment incorporated with the clip thereof, parts of the clip being shown broken away and in section to illustrate structural detail, the pen being shown inserted in a pocket of a garment.

Figure 2 is a view similar to Figure 1 but showing the operative position of the cam as the writing implement tends to ride out of the pocket.

Figure 3 is a detail sectional view taken on the line 3-3 of Figure 1 looking in the direction of the arrows.

Referring to the drawing in detail, wherein similar reference characters designate corresponding parts throughout the several views the letter A generally indicates my attachment for the resilient clip C of a fountain pen F.

The fountain pen F can be of any preferred character or make and includes the barrel 5 and the removable cap 6.

15 The resilient clip C can also be of any preferred character and is anchored to the cap 6 in any desired way. The resilient arm 7 of the clip extends along the cap 6 and preferably terminates in a hollow head 8.

20 My anti-loss attachment A includes a cam or eccentric 9 and the same is mounted in the head 8 for rocking movement. A pivot pin 10 is carried by the head and supports the cam for turning movement. The cam normally projects slightly beyond the inner edge of the head and spring arm and the extremely high point thereof can be provided with a tooth 11. The tooth can be omitted, if the use thereof is found unnecessary.

The outer face of the cam can be provided with a stop shoulder 12 which is adapted to engage the head 8 when the high point of the cam is swung outward so as to prevent the high point of the cam from rolling past the pocket.

25 The sides 13 of the head 8 embrace the opposite faces of the cam and prevent lateral shifting of the cam on the pivot pin. The outer arcuate wall 14 of the head 8 substantially hides the cam from view of the casual observer. Hence the cam does not detract from the appearance of the pen or clip.

30 In use of my attachment, the pen is slipped in the pocket in the ordinary way with the clip against the outer surface of the pocket. As the pen is pushed down in the pocket the cam is normally swung back against the arm 7 of the clip to an inoperative position, as is clearly shown in Figure 1 of the drawing.

To remove the pen from the pocket, it is merely necessary to insert the finger under the free end 35 of the clip against the cam and hold the cam against rolling movement. The pen can now be pulled from the pocket and the cam will still remain in its inoperative position.

With the pen in the pocket as shown in Figure 1, should there be any tendency of the pen

to ride from the pocket, the upward movement of the clip and the ride of the cam on the pocket will swing the cam towards its high point. This will automatically increase the tension of the arm of the clip and consequently the pen will be held tight in the pocket. Obviously, the greater the pull on the pen the further the cam will roll towards its high point and consequently the greater the pull on the pen the greater the tension of the clip.

Where the tooth 11 is used and the cam rolls to its extreme high point the tooth will ride into the fabric of the pocket and further prevent the accidental withdrawal of the pen. The shoulder 12 prevents the too far rolling of the cam as previously described.

While I have illustrated a pen in the drawing and described a pen in the specification, it is to be understood that my attachment can be used with resilient clips for any purpose, such as pencils, combs, rulers, etc.

Changes in details may be made without departing from the spirit or the scope of my invention but what I claim as new is:

The combination with a body having a spring 25

clip with its lower free end normally urged toward said body, a hollow head on the lower end of said clip, of an anti-loss attachment for the body including a cam pivotally mounted for turning movement in said hollow head and having its outer edge protruding beyond the inner face of the clip and head at all times and projecting toward said body, and a shoulder on said cam for engaging said head to limit the outward swinging movement of the cam.

GILBERT M. BRUECKNER.
